UNITED STATES PATENT OFFICE.

JOHN R. MCGIFFERT, OF DULUTH, MINNESOTA, ASSIGNEE TO CLYDE IRON WORKS, OF DULUTH, MINNESOTA, A CORPORATION OF MAINE.

CABLEWAY-SKIDDING MACHINE.

Application filed October 19, 1921. Serial No. 508,897.

To all whom it may concern:

Be it known that I, JOHN R. MCGIFFERT, a citizen of the United States, and a resident of Duluth, county of St. Louis, and State of Minnesota, have invented a new and useful Improvement in Cableway-Skidding Machines, of which the following is a specification, the principle of the invention being herein explained and the best mode in which I have contemplated applying that principle, so as to distinguish it from other inventions.

The present invention, relating, as indicated, to a cableway skidding machine, is more particularly directed to certain features of such a machine relating to the mounting and construction of the spar over which the various operating cables pass. The present invention relates then particularly to an improved type of spar for use on machines of the character referred to, or similar machines, the principal object of the invention being the provision of a spar of simpler and more rigid construction than those formerly used, and one which may be readily adjusted to meet the requirements of various machines as regards the mounting of the pulleys or blocks through which the cables pass. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:—

Fig. 1 is a side elevation of a cableway skidding machine in which my improved invention is incorporated; Fig. 2 is a front elevation of the same; Fig. 3 is an enlarged view in section of the adjusting means for one of the supporting legs of the spar; Fig. 4 is a vertical rear elevation of a spar showing the mounting of one of the pulleys; Fig. 5 is a vertical longitudinal section through the upper portion of the spar; and Fig. 6 is a side elevation of one of the buffer springs carried in the lower portion of the spar.

In Fig. 1 there is shown a cableway skidding machine comprising a car 1 consisting

of a platform mounted upon trucks 2 and 3 in such a way that the platform may tilt slightly transversely of the trucks. On the platform there is mounted an engine 4 for operating various cable-receiving drums 60 which will be referred to presently.

At the forward end of the car there is mounted a spar 5. This spar 5 consists of two legs 6 and 6' which each extend vertically upward for a short distance and then converge, as shown in Fig. 2; the upper portion 7 of the spar being rigidly attached to the adjacent upper ends of the legs 6 and 6'. The spar is pivotally mounted about a horizontal axis in the form of pins 8 and 8', 70 which pass through the lower ends of the two legs 6 and 6' carried in suitable brackets 9 and 10 mounted on the platform 1. The bracket 9 is in turn pivotally mounted about an axis disposed longitudinally of the platform 1 so that it may be tilted transversely of the car, while the bracket or block 10 is provided with an opening 11 adapted to be brought into registration with one of the three openings 12 formed in the 80 platform and there fastened by means of a pin 13 to variously adjust the elevation of the legs 6. The effect of this vertical adjustment of this leg is to tilt the entire spar about its axis in the bracket 9, for purposes which will be described hereinafter.

The upper portion 7 of the spar is hollow and is adapted to receive a sleeve therein, this sleeve 15 being provided with a horizontally extending flange 16, which 90 rests upon the upper end of the spar, and which has a series of downwardly extending lugs 17 with openings 18 adapted to receive guy ropes therein for guying the spar. Inside of the sleeve 15 there is 95 mounted a bracket 19 which fits snugly into the sleeve, but is rotatable therein. This bracket is provided with a flange 20 which rests upon the flange 16 on the sleeve and has an upwardly extending portion within 100 which is journaled a pulley 21, which, in the mechanism shown in the drawings, carries the trolley cable 22. The trolley cable 22 passes from the pulley 21 down through the spar 7 to the trolley drum 21', the arrangement being such as to permit the cable 22 to be run freely in any direction from the top of the spar 7. Aligned with the pulley 21 105 is a block 23, which is also mounted in the upper portion of the bracket 19 for carry- 110

ing a block 24, around which passes the tightening cable 25, which also passes around a lower block 26, to which are attached guy wires 27. These guys 27 are 5 tightened by means of the cable 25, which passes from the pulley 24 downward and over the drum 28, the operation of which will be described later.

The spar may be lifted to the desired 10 elevated position, but is limited by means of a framework 30, against which there contact two buffers 31, which are mounted upon coiled springs 32 carried in tubes 33 in the legs of the spar. The buffers 31 15 serve to prevent jarring of the spar and possible injury when it is raised, while the framework 30 limits the vertical position of the spar. The spar is raised until the springs 32 have been somewhat compressed 20 and is then guyed in that position, when the springs and framework constitute a resilient automatic adjusting means for the slight swinging of the spar in the longitudinal plane of the car.

25 The hoisting cable 35 passes over the pulley 36, mounted on the spar, and then down to a hoisting drum 37. The slack-pulling cable 38, for pulling slack in the hoisting or skidding cable, passes over a 30 pulley 39 and then down to the slack-pulling drum 40, while the out-haul cable 41 extends over a pulley 42 and then down to an out-hauling drum 43. The mounting of each of the pulleys 36, 39 and 42 is exemplified in Fig. 4, in which the pulley 36 is shown mounted in a U-bolt 45 which is suspended from a bracket 46. This bracket is mounted about a vertical axis in the form 35 of a pin 47, which is mounted on the rear face of the spar 7, the pulley 36 being permitted to swing freely at the side of the spar and to tilt to whatever vertical position is required.

40 The spar in the present construction is mounted to swing vertically into the desired vertical position, and is then automatically adjusted in that position by means of the buffers and frame 30 to permit it to give slightly either toward or away from the other support for the trolley cable, which 45 may be a tree or post 50 mounted in line with the major axis of the car 1. At the

same time the spar is permitted to tilt or to be adjusted transversely of the car, and it is desirable to tilt the spar so that the various pulleys 36, 39 and 42 will swing freely at the side of the spar and will hang in vertical positions. If the spar were in a central position the various pulleys would be thrown off center a distance equal to 55 half the width of the spar plus half the width of the pulley, together with the necessary clearance between spar and pulley, which would give an undesirable side lead to the cables in winding them on their 60 proper drums. By tilting the spar slightly to one side the various blocks or pulleys may be mounted in a perfectly vertical position, and substantially centrally with respect to the drums, through which their 65 cables pass.

70 Other modes of applying the principle of my invention may be employed instead of the one explained, change being made as regards the mechanism herein disclosed, 75 provided the means stated by any of the following claims or the equivalent of such stated means be employed.

I therefore particularly point out and distinctly claim as my invention:— 80

1. In a machine of the character described, the combination of a platform, a spar having spaced legs pivotally mounted in aligned brackets horizontally arranged on said platform, one of said brackets being 85 pivotally mounted on said platform on an axis at right angles to the pivot of said legs, and the other of said brackets being mounted for vertical adjustment on said platform. 90

2. In a machine of the character described, the combination of a platform, a spar having spaced legs pivotally mounted about horizontal axes, a sheave-carrying bracket pivotally secured to one side of said 95 spar, said bracket normally being parallel with said spar, and means adapted to vertically adjust one of said legs to tilt the spar, whereby the sheave bracket is suspended at an angle to said spar and away from the 100 side thereof.

Signed by me, this 19th day of September, 1921.

JOHN R. McGIFFERT.
